United States Patent

Des. 236,277
Patented Aug. 12, 1975

236,277

TOY CONSTRUCTION PIECE

Jack G. McAllister, 2701 N. Douglas Drive, 55422, and
Richard O. Bartz, 7017 Mark Terrace Drive, 55435,
both of Minneapolis, Minn.

Filed Feb. 12, 1973, Ser. No. 331,503

Term of patent 14 years

Int. Cl. D21—01
U.S. Cl. D34—15 GG

FIG. 1

FIG. 2

FIG. 1 is a front plan view of a toy construction piece showing our new design; and

FIG. 2 is a side elevational view thereof.

We claim:

The ornamental design for a toy construction piece, substantially as shown and described.
